UNITED STATES PATENT OFFICE

170,185

DRILL UNIT

Andrew B. Crichton, Jr., Johnstown, Pa.

Application April 4, 1952, Serial No. 19,195

Term of patent 14 years

(Cl. D54—14)

To all whom it may concern:

Be it known that I, Andrew B. Crichton, Jr., a citizen of the United States, residing at Johnstown, State of Pennsylvania, have invented a new, original, and ornamental Design for a Drill Unit, of which the following is a specification, reference being had to the accompanying drawing, forming a part hereof.

Fig. 1 is a perspective view looking from one end of a drill unit embodying my new design;

Fig. 2 is a perspective view looking from the opposite end;

Fig. 3 is a side elevation; and

Fig. 4 is a top plan view thereof.

The characteristic features of the present design are shown by full lines in the drawing.

I claim:

The ornamental design for a drill unit, as shown and described.

ANDREW B. CRICHTON, JR.
